United States Patent

Des. 234,654
Patented Apr. 1, 1975

234,654

HOLDER FOR SOAP AND OTHER ARTICLES

Ann Woody, Rte. 1, Box 107F, Otis, Oreg. 97368

Filed July 15, 1974, Ser. No. 488,474

Term of patent 14 years

Int. Cl. D23—02

U.S. Cl. D6—90

FIG. 1

FIG. 2

FIG. 3

FIG. 4

FIG. 1 is a perspective view of a holder for soap and other articles showing my new design;

FIG. 2 is a side elevational view of the holder taken from the right side of FIG. 1;

FIG. 3 is a front elevational view of the holder; and

FIG. 4 is a top plan view of the holder.

I claim:

The ornamental design for a holder for soap and other articles, as shown.
